UNITED STATES PATENT OFFICE.

EUGENE PLOURDE, OF PATERSON, NEW JERSEY.

BILL-FILE.

No. 846,946.

Specification of Letters Patent.

Patented March 12, 1907.

Application filed October 19, 1906. Serial No. 339,599.

To all whom it may concern:

Be it known that I, EUGENE PLOURDE, a subject of the King of England, residing in Paterson, county of Passaic, State of New Jersey, have invented certain new and useful Improvements in Bill-Files; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my invention is to provide a system for use by grocers and the like store-keepers whereby to substantially entirely, if desired, eliminate bookkeeping and make the matter of keeping accounts with their customers extremely simple, as well as easy of verification.

In carrying out my invention I employ as a part of the system the bill-file or cabinet illustrated in the accompanying drawings, wherein—

Figure 1 is a front elevation of said cabinet. Fig. 2 is a side view thereof, partly in section. Fig. 3 is a view in section on the line $x-x$ in Fig. 2, the rear lower part being shown as broken away. Fig. 4 is a vertical sectional view on the line $y-y$ in Fig. 2. Fig. 5 is a perspective view of one of the bill-holders, and Fig. 6 shows one of the bills.

The cabinet comprises a back a , two horizontal side walls b , two inclined side walls c , the latter connecting the walls a and b , and a bottom wall d . Between the side walls b and on the bottom wall d slides a drawer or till e , which in its closed position meets an abutment f , forming, with the bottom wall d , said walls b , and back wall a , a compartment in which the bills, &c., may be placed. This compartment has a cover g , which is hinged to a horizontal front wall h between the lower ends of the inclined side walls c in such manner that it covers the till as well as the compartment.

Between the drawer or till and the cover g and against the side walls b are arranged horizontal guides i , on which runs a slide k in the form of a rectangular frame (see Fig. 4) and rabbeted, as at l , to receive a holder m for a paper sheet n and glass o , the holder being of sheet metal and having its side

edges overlapping the sheet and glass, as at p , so that the latter are held in place, but 55 may be removed upon removing the holder and sliding them out of the same. On the paper sheet is adapted to be inscribed the names of the customers with numbers opposite them (not shown) corresponding to the 60 bill-holders hereinafter described, so that the whole forms a sort of directory to the bill-holders on which nothing is normally exposed but numbers or the like. The slide k has two rearward extensions q , whereby it may be 65 pulled clear out and yet be guided and held on the guides i .

On the wall h is a bead r , forming an abutment, and between the two side walls c is another inclined wall s , which forms with the 70 inclined walls c and the abutment r a pocket for the bill-holders and their mountings. Each of said mountings consists of a wall t and two side strips u , which project above the wall t and are secured thereto, as by 75 screws v . There are as many of the mountings as desired—say, four, as in Fig. 1—and they are all held together by pins w , having their ends upset or riveted. In each mounting is arranged a series of bill-holders x , each 80 of which (see Fig. 5) is a sheet-metal plate having its two side edges y turned up, as also an intermediate portion z at its lower end, so as to prevent the bills placed therein from sidewise and downward movement. The 85 series of mountings being all held together by the pins w may be bodily removed, with their bill-holders, from the cabinet for placing in a safe at night or any other purpose. In each holder is a clip 1, consisting of a wire rebent 90 and having its ends 2 coiled about the pin w , so that the clip is pressed against the tills in the holder. (See Fig. 5.) Each clip also acts to press each holder against its neighbor above it, all the holders thus being normally 95 held in the position shown in Fig. 2 in full lines, but being capable of being turned out on its pivot, as shown in dotted lines.

The bill adapted to be used in connection with my system is that shown in Fig. 6, which 100 has a space at 3 wherein to insert the total of a previous bill or bills. When an order is made out in the store for a person running an account, the clerk enters the items and the charges therefor on one of these bills and 105 places the same in the bill-holder assigned to

that particular customer, which he ascertains by number from the directory; but before filing the bill, a copy of which goes to the customer, he enters the total of previous bills already filed in the space 3, so that the customer and the proprietor can tell at once at any time what is owing. The last bill filed, therefore, always shows the full account of any particular customer, and when the account is settled the bills in the holder may be destroyed or handed over to him.

Instead of utilizing the first holder in each series in Fig. 1 for customers having an account, since it is undesirable to expose what their accounts are to others, these holders may be utilized for such business as C. O. D. bills or for bills for goods which are to be delivered at a future date by given wagons or employees, ("W. No. 1," &c., in Fig. 1 standing for "Wagon No. 1") or otherwise.

Having thus fully described my invention, what I claim as new, and desire to secure by Letters Patent, is—

The combination of a cabinet comprising an inclined pocket and a horizontally-disposed wall-inclosed space below said pocket, a hinged cover for said space, a drawer occupying a part of said space, a directory-slide arranged above said drawer in said space, and bill-holders arranged in said pocket and a mounting removably supported in said pocket and carrying said bill-holders, substantially as described.

In testimony that I claim the foregoing I have hereunto set my hand this 11th day of July, 1906.

EUGENE PLOURDE.
